UNITED STATES PATENT OFFICE.

FREDERICK A. ROBINSON, OF ROSLINDALE, MASSACHUSETTS.

AIR-PREHEATING ATTACHMENT FOR OIL BURNERS.

Application filed July 11, 1925. Serial No. 42,933.

This invention relates to liquid fuel burners and particularly to air pre-heating attachments therefor, and has for its object to provide a novel device which may be detachably mounted upon that type of burner, said device being so connected to the base member of said burner that air may pass upwardly through said burner and then be conducted in a serpentine or circuitous path thereabove in such a manner that it will be exposed to the heat of the flame from said burner, the heated air then being discharged downwardly toward the fuel nozzle of said burner where the air will aid in the vaporization of the fuel, causing a complete combustion of the latter and an extremely hot and efficient flame.

In the embodiment of my invention selected for illustration and description here-
20 in,

Figure 1 represents a plan of one form of an oil burner and an air pre-heating attachment therefor embodying my invention; and

25 Fig. 2 is a central vertical section taken on the line 2—2 of Fig. 1.

Like numerals refer to like parts throughout the several views of the drawings.

In the drawings, 5 represents the base member of a burner of the type frequently employed in furnaces, heaters and the like, and utilizing oil as a fuel. The base member 5 has an air chamber 6 and is also provided at one end with a depressed top portion surface or oil trap 7 at the center of which an oil distributing nozzle 8 is mounted, said nozzle having a fuel supply pipe 9 communicating therewith.

The base member 5 has a herein circular neck 10 projecting upwardly from the upper surface at one end, and forming an air outlet 11 from the air chamber 6. Mounted upon the base 5 is an air conductor or H-shaped flue member 12 embodying therein an upright flue 13 having an inlet air passage 14 extending therethrough and communicating with the passage 11 in neck 10, and a second flue like portion 15 having a discharge passage 16 for air extending therethrough, said portions 13 and 15 being joined together near their lower ends by an intermediate connecting rib portion 17, forming with the flue walls an air heating chamber 18 communicating with the discharge passage 16. This air heating cham-

ber acts to heat the air therein to a high degree of temperature as the chamber is provided with only a small opening, with the result that the air therein circulates very slowly, if at all. This hot air chamber acts 60 in turn not only to prevent the webs 12 and 17 from becoming overheated, but it also acts to maintain just beneath the main air preheating member to be presently described, a constantly high temperature 65 which effectively maintains in the said preheater a high temperature not only while the burner is in operation, but also after it has been shut off, such a high degree of temperature as to prevent the said preheater 70 from cooling rapidly, thus maintaining it in a heated condition in anticipation of its use as soon as the burner is again put in operation. This H-shaped flue member makes it possible to support the flue 15 from 75 and by the flue 13 without supports on or near the burner of the flue 15, these supports of any kind being always an objectionable feature because they collect soot and dirt and also interfere with the free space for 80 the flame. Furthermore, the H-shaped flue member enables me to connect the flues with the preheater without bolts or screws which warp under heat and throw the members out of alignment, particularly the preheater, and thus interfere with the effectiveness 85 of the burner. Again, the parts being unbolted may be readily separated in the fire pot of the heater which could not otherwise be done. The flue 13 of the air flue member 90 12 rests at one end upon the upper surface of the base member 5 and receives therein the neck 10 about which it is adapted to turn when occasion demands, as will be hereinafter more fully set forth.

The flue 13 of the air flue member 12 has an arc-shaped flange 19 formed integral therewith at the lower end thereof in which a hole 20 is provided and which receives a projection 21 formed upon the upper surface of the base member 5 and acts to hold the flue member 12 in its normal position with the opening of the discharge passage 16 located directly above the fuel nozzle 8.

The flange 19 and projection 21 serve to 105 support the member 12 when it is desired to clean the fuel nozzle 8, or for other reasons it may be desirable to swing the flue member 12 from its normal position above said fuel nozzle. At such times the air flue member 110

12 is raised upon the neck 10 until the flange 19 clears the top of the post 21, and said flue member is then swung either to the right or left into a position where convenient access may be had to the fuel nozzle 8 to clean it at which time the flange 19 will rest upon the top of the post 21.

The upper end of the flue 13 of the flue member 12 has a flange 22, and the upper end of the flue 15 of said flue member has a flange 23 formed to receive suitable packing. Mounted upon the top of the flue member 12 and connecting said flues 13, 15, for effectively pre-heating the air for the burner is a pre-heating member 24, having therein an inlet neck 25 a discharge neck 26, and an intermediate serpentine-shaped or circuitous conduit portion 27. The inlet neck 25 rests, as stated, within the neck 13 and communicates with the inlet passage 14, while the neck 26 of said heating member 24 rests within the neck 15 and communicates with the discharge passage 16 thereof. A suitable packing material 28 is located within the flange 22 for the purpose of making the joint tight, and similar packing material 29 is located within the flange 23 for a similar purpose.

The general operation of the device is as follows: Assuming that the various parts are positioned as illustrated in the drawings, and fuel oil is being delivered to the nozzle 8 through the fuel supply pipe 9, air passing upwardly through the base member 5 of the burner and through the air outlet 11 formed therein passes through the air passage 14 of the flue member 12 and into and through the flue connecting preheater 24 from which said air passes downwardly through the passage 16 of the flue member 12 and is delivered against the upper surface of the fuel nozzle 8.

The oil is first ignited in any well known manner, as by a wick provided for the purpose upon the base of the burner, and the flame passes upwardly around the flue member 12 and between the bonds or turns of the serpentine-shaped flue connector and pre-heater 24, thereby effectively pre-heating the air that is delivered to the fuel nozzle, and said heated air aids materially in vaporizing the fuel as it is discharged from the nozzle, with the result that there is a more complete combustion of the fuel and a very hot and efficient flame is produced. The heated air furthermore, tends to reduce the amount of soot that is generally created when unheated air is delivered to the burner.

When it is found necessary to clean the fuel nozzle, the same is accomplished, as stated, by raising the flue member 12 and the heater 24 mounted thereon until the flange 19 becomes disengaged from the locking post 21; after which said members may be swung to either side of the nozzle about

the neck 10 as may be desired. At such times, the flange 19 rests upon the upper extremity of the post 21.

Claims:

1. In combination, a burner base, an air flue member mounted upon said base and provided with inlet and discharge flues and an air heating chamber, an air heating member mounted upon said flue member and communicating with said flues, said flue member discharging heated air from said heating member above said base.

2. In combination, a burner base, an air flue member mounted upon said base and provided with inlet and discharge flues and an air heating chamber, an air heating member of serpentine form mounted upon said flue member and communicating with said flues, said flue member discharging heated air from said heating member downwardly against said base.

3. In combination, a burner base provided with an air passage extending therethrough and an oil trap, and a neck, an H-shaped air flue member mounted upon said base and adapted to swing upon said neck, said flue member being provided with an inlet flue communicating with the air passage of said base and also with a discharge flue, and a multi-folded air heating member mounted upon said flue member and communicating with said inlet and discharge flues, said member discharging heated air from said heating member above said base.

4. In combination, a burner base provided with a burner and an air passage extending therethrough, the base having a neck, an air flue member for air mounted upon said base and adapted to swing upon said neck, said conductor being provided with an inlet passage communicating with the air passage of said base and also with a discharge passage extending therethrough, an air heating member with a zig zag passage mounted upon said flue member and communicating with said inlet and discharge flues, said member discharging heated air from said heating member above said base, and means upon the base to interlock with said flue member and hold the latter in its normal position thereon.

5. In combination, a burner base provided with an air passage extending therethrough, a burner, an oil trap, the base having a neck, an air flue member for air mounted upon said base and adapted to swing upon said neck, said flue member being provided with an inlet passage communicating with the air passage of said base and also with a discharge passage, an air heating member with a sinuous passage mounted upon said member and communicating with said inlet and discharge flues, said members discharging heated air from the heating member above the base, and means comprising a post upon

5 said base to interlock with said flue member and hold the latter in its normal position thereon, said member also having a supporting flange formed thereon adapted to engage said post when said flue member is raised and swung into an abnormal position relatively to said base.

10 6. Liquid fuel heating means comprising a base member having an air outlet, a burner, a flue member supporting post on the base, a flue member comprising a plurality of flues and a heating chamber, an air preheating member providing a circuitous path connecting said flues, a flue member having an 15 arc-shaped flange at its lower end constructed and arranged to ride upon said supporting member when the former is turned about the base air outlet to permit access to the nozzle when disassembling the several parts.

20 7. Liquid fuel heating means comprising a base member with a burner and an air outlet, a flue member thereover having an upright flue connecting with the base air outlet, a second upright flue positioned over the 25 burner, and a serpentine shaped air preheating member connecting the upper ends of said flues.

8. Liquid fuel heating means comprising a base member having an air outlet and a

burner, a flue member therefor comprising 30 a plurality of flues with a heating chamber therebetween, one for registering with the base air outlet and a second flue registering with the burner, and an air preheating member providing a tortuous path between the 35 flues.

9. Liquid fuel heating means comprising a base with a burner and an air outlet, a flue member with a plurality of flues, one of which registers with the air outlet of the 40 base, while a second flue has an outlet adjacent the burner, and a flue connecting air preheating member folded upon itself a plurality of times and providing a passage with a plurality of folds between said flues. 45

10. Liquid fuel heating means comprising a base member having an air outlet and a burner, a flue member therefor, comprising a plurality of flues, one of which supports a second flue over the burner, one flue registering 50 with the base air outlet, and an air preheating chamber supported between and by said flues and providing a tortuous path therebetween.

In testimony whereof I have hereunto set 55 my hand.

FREDERICK A. ROBINSON.
